UNITED STATES PATENT OFFICE

95,579

DESIGN FOR A GLASS PLATE OR ARTICLE OF SIMILAR NATURE

George S. Dunbar, Columbus, Ohio, assignor to
The Federal Glass Company, Columbus, Ohio, a corporation of Ohio

Application March 12, 1935, Serial No. 55,853

Term of patent 14 years

To all whom it may concern:

Be it known that I, George S. Dunbar, a citizen of the United States of America, residing at Columbus, in the county of Franklin and State of Ohio, have invented a new, original, and ornamental Design for a Glass Plate or Article of Similar Nature, of which the following is the specification, reference being had to the accompanying drawing, forming a part thereof.

I claim:

The ornamental design for a glass plate or article of similar nature, as shown.

GEORGE S. DUNBAR.
